LOG SHAPING MACHINE

Edward Wilson, Dubois, Idaho

Application June 8, 1948, Serial No. 31,661

5 Claims. (Cl. 142—54)

1

The present invention relates to improvements in wood working machines for turning, cutting, or trimming rough solid or tubular cylindrical work to a uniform exterior diameter, or circular cross section, and more specifically to an improved log shaping machine which while adapted for various purposes and uses, is especially designed for shaping logs and/or poles throughout their length with uniform diameters, smoothly finished or polished exterior surfaces, and one or more exterior longitudinally extending joint-grooves; and the finished product of this machine may subsequently be manufactured into structural building units.

In its physical embodiment the log-shaping machine of my invention employs a planetary arrangement of a revolving tubular head and its rotary cutters through which assembly a non-rotary rough log is fed by power operated reciprocable railway carriages, under control of an operator occupying a seat on one of the carriages.

Means are provided for feeding or successively supplying rough logs from one side of the machine to the carriages, and for laterally discharging the shaped and trimmed logs or finished work from the opposite side of the machine. The machine involves the use of a minimum number of standardized parts having self-contained power units or servomotors under manual control, which may be assembled and installed with convenience, to provide a smooth working, quick-acting, precision machine that is efficient and accurate in the performance of its required functions.

The invention consists in certain novel features of construction and combinations and arrangements of parts as will hereinafter be described and more particularly set forth in the appended claims. In the accompanying drawings I have illustrated a complete example of a physical embodiment of my invention wherein the parts are combined and arranged in accord with one mode I have devised for the practical application of the principles of my invention. It will however be understood that changes and alterations are contemplated and may be made in these exemplifying drawings and mechanical structures, within the scope of my claims, without departing from the principles of the invention.

Figure 1 is a top plan view of a log-shaping machine embodying my invention, foreshortened and broken away for convenience of illustration.

Figure 2 is a vertical transverse sectional view at line 2—2 of Fig. 1 showing the log-feeding or supply ramp.

2

Figure 3 is a transverse vertical sectional view at line 3—3 of Fig. 1 facing the hollow or tubular rotary cutter head.

Figure 4 is a foreshortened view in side elevation, with parts in section, showing the two railway carriages and the aligned log-clamping members.

Figure 5 is another foreshortened view in side elevation showing the carriages, and the driving means for the cutter-carriage.

Figure 6 is a vertical sectional view showing the dust-fans, collectors, and conveyors; and Figure 7 is a transverse vertical sectional view showing the groove-cutters, and dust conveyors.

Figure 8 is an enlarged, longitudinal, vertical, sectional view through the tubular cutter head showing the rotary trimming cutters and the groove-cutters; and Figure 9 is a horizontal detail sectional view at line 9—9 of Fig. 8.

Figure 10 is a detail view showing a transverse portion of the tubular cutter head with one of the abrasive or polishing blocks; and Figure 11 is a sectional view at line 11—11 of Fig. 10.

Figures 12 and 13 are detail views of the polishing pads or blocks, detached.

Figure 14 is a face view of one of the four rotary cutters; and Figure 15 is a sectional detail view at lines 15—15 of Fig. 14.

In carrying out my invention the operating parts of the machine are supported upon a suitable concrete base, bed, or foundation F having track rails R, and provided with a main dust-conveyor duct D extending longitudinally beneath the machine, and provided with a screw or spiral conveyor S that is adapted to receive chips, cuttings, and debris through a down-chute C, while other loose material or debris from the machine is conveyed to duct D by way of a lateral duct E. An impeller or rotary fan blower G draws dust and loose debris from a collecting hopper H located in appropriate position, and the impeller discharges the waste material to the main duct.

Successive logs L are supplied, broadside, from one side of the machine, on a supply ramp I, to the two connected railway carriages A and B, and after the logs are trimmed and shaped they are discharged at the opposite side of the machine upon a ramp, M, from which ramp the finished logs are conveyed for subsequent operations. The power carriage or propelling carriage A, and the holder-carriage B, which support the log during the trimming operations, are provided with wheels W, and the carriages are operatively connected by an open rectangular supporting

frame that includes a pair of upper tubular longitudinally extending parallel bars 1, 1, and lower bars 2, 2, rigid with the holder-carriage, and these four bars are rigidly united by end heads 3 and 4 of the carriage frame. These bars 1 and 2 are mounted in and pass through the carriage A to permit relative movement of the carriage with relation to the frame and carriage B, and carriage A is equipped with a ram 5. Carriage B is equipped with a work holder or log holder 6 and mounted on the adjoining inner ends of the ram and work holder are clamping heads 7 and 8 respectively, between which clamping heads the log L is supplied from the supply ramp I, and then rigidly clamped.

In this rigidly clamped position between the two carriages the rough log is fed to and through the stationary cutting unit that includes a hollow tubular or cylindrical revolving cutter head 9, four rotary cutters 10 mounted in planetary arrangement on and around the revolving tubular cutter head, and two rotary groove cutters, 11, 11.

As best seen in Fig. 8, the tubular cutter head 9, through which the log and its holders pass, is journaled in spaced exterior bearings 12, 12, mounted in a frame 13 upon a fixed base 14, and the cutter head is operated by power from an electric motor 15, as seen in Fig. 1, through a sprocket and chain drive 16 to a driven sprocket 17 mounted transversely on the exterior of the cutter head between the spaced bearings 12, 12.

The cutters 10 revolve with the cutter head around the periphery of the advancing log, and rotary movement is imparted to the cutters from the cutter head by means of an internal gear ring 18 fixed on the exterior of the cutter head, which ring meshes with and drives a pinion 19 on the arbor 20 of each rotary cutter. The arbors are journaled in bearings 21, 21, mounted in a bearing ring 22 fixed on the exterior of the cutter head to revolve therewith. In the detail Figures 14 and 15 the arbor 20 of each rotary cutter 10 is fashioned with a flanged hollow head 23 and a central boss 24 having a threaded stud, and the cutter is clamped against the head by nut 25 threaded on the stud. The four cutters project from the working face of the cutter head in position to act on the periphery of the advancing log, and each cutter is here shown as equipped with peripheral teeth 26, and a series of conical or tapered teeth 27 for trimming the periphery of the rough log, and an annular series of spur teeth 28 for smoothing the trimmed log.

As an additional aid in smoothing the trimmed log an annular abrasive band 29 is resiliently mounted in a groove between the flanged head 23 of the arbor and the cutter, and this abrasive band may readily be replaced when worn.

Chips and cuttings from the rotary cutters are disposed of by means of a rotary fan or impeller 30 mounted on the exterior of the bearing head or ring 22 of the cutter head and surrounding the cutters, and the fan is enclosed within a protective housing 31 rigid with the base 14. The cuttings, by centrifugal force of the rotating impeller are directed into the down-chute C, through which they fall into the main conveyor duct D.

In addition to the abrading bands 29 of the rotary cutters the rotary cutter head, at its rear end is equipped with a number, as three, circumferentially spaced polishing pads or sanding blocks, each resiliently mounted in an end

slot 32 of the cutter head, and designed to bear against the exterior surface of the trimmed log as it passes through the cutter head. Each polishing pad includes a holder 33 that is hinged on the exterior of the cutter head at 34 in suitable ears or brackets, and a replaceable polishing or abrading element 35 is retained in the holder by a pair of spring cleats or resilient clips 36, an elastic sponge backing 37 being provided for the abrading or polishing element.

The polishing pads are eccentrically mounted in the slots 32, so that by centrifugal force of the revolving cutter head, the pads tend to swing outwardly from the slots as indicated in Fig. 11, but their movements are limited by stops or pins 38. As the forwardly advancing log contacts these pads, they are automatically swung into parallelism and frictional engagement with the log, and by pressure thereon the pads polish the surface of the trimmed log.

The upper and lower rotary cutters 11, 11, which fashion two diametrically arranged longitudinally extending exterior joint-grooves in the trimmed log L are located at the rear of the cutter head, and mounted for vertical adjustment upon two spaced columns or posts 39, 39 rigid with a fixed base 40.

Each groove cutter 11 is rigidly mounted upon a horizontally extending spindle 41 which is arranged transversely of the longitudinal axis of the machine and journaled in spaced bearings 42 in a pair of vertically adjustable and opposed bearing blocks or frames 43, 44. The adjoining faces of the bearing blocks are grooved to fit the two posts and they are clamped on the posts or columns by means of spaced bolts 45 and their nuts.

For vertically adjusting the two groove cutters with relation to the log L, a pair of upright screw bars 46, 46 are journaled at their upper ends in bearings of a cross-head 47 that is clamped on and rigidly unites the two posts, and these screw bars are threaded through the bearing blocks of the upper and lower cutters. By means of a wrench or other hand tool applied to the upper squared ends 48 of the screw bars the adjusting bars may be turned to vertically adjust the cutters 11, 11, as desired.

For disposing of the dust and chips from the two groove-cutters 11, 11, the spindles 41 of the cutters are each equipped with a fan blower or impeller 49 that rotates with the spindle to impel the dust from the cutters downwardly to the collecting hopper H, and then the impeller fan G blows the dust to the screw conveyor S and main duct D.

The two groove cutters are operated by motors 50 and 51 mounted on a frame 52, which is slotted and adjustably supported by bolts 53 on the housing 31 of the cutter head, and sprocket chain drives 54 from the motors transmit power to a driven sprocket 55 on the spindles 41.

The loading mechanism for supplying successive logs broadside from the loading ramp I to the carriages A, B, is mounted at one side of the machine in a frame 56 of the ramp I, and the mechanism is actuated and automatically controlled by the reciprocating movements of the two carriages. For this purpose a longitudinally extending rock shaft 57 at its ends is journaled in the frame 56, and the shaft is equipped with a series of spaced hooks or carriers 58 in the shape of compound curves that terminate in end lugs 59, and these hooked carriers in initial position

rest with their lugs 59 on resilient or elastic stop bars 60 attached at the underside of the ramp I. The hooked ends of these carriers form cradles for a log that is rolled into the cradle from the ramp I, and then the log is swung through an arc of one hundred and eighty degrees into axial alignment with the two clamping heads 7 and 8 of the carriages.

For rocking or oscillating the shaft 57 of the loading mechanism, a pair of bevel pinions 61, 61, 10 are rigidly mounted on its ends, and a pair of larger actuating gears 62 and 63 are journaled in bearings of the frame 56 for engagement with the respective pinions. Each of the actuating gears is equipped with a crank arm 64 having a cam head 65, and cam plates 66 and 67 mounted on the sides of the respective carriages A and B are adapted to alternately contact with and ride down one of the cam heads 65 for rocking the shaft.

As illustrated in Figures 1 and 2 the crank arms 64 are fixedly mounted on gears 62 and 63 and as the heads 65 are engaged by the cam plates 66 and 67, respectively, the heads 65 are forced downwardly rotating the large beveled gears and these gears, in turn, rotate the pinions whereby the shaft 57 is rotated from the position shown in Figures 2 and 3 through an angle of substantially 180 degrees, depositing a log in the holders 71. With continued movement of the carriages the 30 cam 67 on carriage B engages the head of the crank arm of the gear 62 and returns the carriers 58 to the log receiving positions shown in Figures 2 and 3.

For resiliently stabilizing and retaining the loading mechanism in correct positions for use, the shaft 68 of the bevel gear 63 may be equipped with a clutch 69 and spring 70, as best seen in Fig. 1.

The carriers 58 of the loading mechanism transfer the log and deposit it into a series of spaced Y-shaped holders 71 located along the longitudinal axis of the machine, and each holder has a leg 72 adjustably fitted in a tubular socket member 73 in which it is locked in adjusted position by means of transverse holes and sockets and a pin or bolt 74. The socket member or extension of the leg, is pivotally mounted or hinged at 74' in a bracket or ears 75 fixed on the foundation F, and the L-shaped leg of the holder is equipped with a counterweight 76 that automatically maintains it in erect position to receive a log. One arm of the Y-shaped holder has a horizontal discharge arm 77, and the two Y-shaped arms of the holder receive and retain the log as it is deposited therein.

These pivotally mounted and counterweighted holders are swung downwardly out of the path of the advancing carriage by contact therewith with the front of the carriage A as it is propelled to the left in Fig. 4 to feed the rough log to the cutter head.

When the rough log has been received by and is held in the holders in axial alignment with the machine, the ends of the log are clamped between the two heads 7 and 8, and for this purpose and operation the tubular ram 5 of the carriage A terminates at its rear end in a hydraulic cylinder 78. The frame head 4 is equipped with a fixed horizontally mounted stem 79 that projects into the cylinder and the stem is equipped with a stationary piston-head 80, which, together with the cylinder forms a hydraulic or fluid pressure motor for advancing the carriage A, ram 5, and its head 7 to clamp one end of the log L with its

other end against the complementary head 8 of the carriage B.

5 The hydraulic motor and ram are under control of an operator who occupies a seat on the carriage A, and manipulates a control lever 81 of a three-way valve 82 supported in suitable manner on the carriage.

Motive fluid for the hydraulic motor is supplied from a tank 83 and its connected pump 84, and the hydraulic motive fluid is alternately supplied to the motor cylinder of the carriage by pipes 85 and 86, a return pipe being indicated at 87, and a pump-supply pipe being shown at 88 leading to the control valve.

The hydraulic pump is operated by a motor 89 through a sprocket chain drive 90, and this motor 89 is also employed as a power plant for propelling the carriage A, in connection with speed reducing mechanism contained in the housing 91.

20 From the speed reducer 91 are extended a forward drive belt 92 and a reverse drive belt 93, passing over pulleys 94 journaled in a fixed frame 95, for co-action with a sprocket chain drive 96 to one of the wheels W of the carriage A. These forward and reverse belts are operated alternately by a belt tightener consisting of a hand lever 97 pivoted at 98 on the frame 95, and this hand lever is equipped with a pair of pulleys 99 for alternate co-action with the forward and reverse belts. By swinging lever 97 to elevate pulley 99 into contact with belt 92 the carriages are propelled forwardly for feeding the log through the tubular cutter head, and by reverse swinging of the lever to depress the rollers 99, the belt 93 is tightened to reverse the travel of the carriages. The idler pulley 94 serves to carry the belt 93 loosely when the belt tightener is elevated to neutral position.

35 At the end of the feeding movement of the machine, and after the trimmed end of the log has passed through and emerged from the cutting unit, the log is released from its clamping heads 7 and 8 by withdrawal of the head 7 from its end of the log. This release is accomplished by manipulation of the hydraulic control lever 81 and its valve to permit introduction of motive fluid pressure to the interior of the cylinder 78 between the right hand side of the piston head and the outer end of the cylinder, which imparts an outward or reverse movement to the carriage 40 A and its ram. It will be understood of course that this release operation of the trimmed log is the reverse of the clamping operation of the rough log L.

45 When the trimmed log is released it drops into another set of the Y-shaped holders, longitudinally spaced along the axis of the machine and indicated at 100. These pivotally mounted and counterweighted holders are held in upright position to receive the released log, and each of 50 these holders has a laterally extending discharge arm similar to but oppositely pointed from arm 77 of the loading holders 71. The pivotally mounted unloading holders 100 are initially depressed by the advancing carriage B, and automatically rise to upright position after passage of the carriage.

55 The discharge arms of the unloading holders direct the trimmed log to the unloading or discharge ramp M and the logs, successively, roll down this declining ramp for subsequent handling.

70 Simultaneously with the release of the shaped log, the operator on carriage A, by manipulating lever 97 shifts the belt-tightener mechanism of

the chain drive 96 that propels the carriages, and the latter are reversely propelled to initial position for reception of another log from the loading holders that has been deposited from the loading ramp.

When shaping logs having large butt-ends, and especially when they are coated with debris, this excess material may be removed by means of four auxiliary chisel-cutters, as 101, spaced circumferentially about the tubular cutter head in position to cut the excess material from the log, and these chisel-cutters, rotatable with the cutter head, are adjustably mounted in brackets or holders 102 bolted on the front face of the cutter head.

Various appliances and adjustments may be made for efficient operation of the machine, as for instance, the heights of the carriages A and B may be adjusted with relation to their supporting wheels by means of slotted plates 103 that are bolted at 104 to the carriages, and these axle-plates support the bearings for the wheels W of the carriages.

In order to insure guidance and maximum precision in the longitudinal feed of the log through the cutter head, the tubular holder 6 of carriage B may be equipped with a tubular telescoping plunger rod 105 that communicates with the hydraulic system of carriage A. A dash-pot plunger rod 106 extends therefrom to an electrical control station 107, and a flexible electrical conductor or cable 108 is adapted to wind upon and unwind from a rotary reel 109. This cable may be extended through one of the tubular rods or bars 1 of the carriage frame to the electric motor 90 that supplies power to propel the connected carriages.

The various electric motors for operating parts of the machine are provided with the necessary equipment for control of the motors, and these controls are located where they are readily accessible to the operator riding on the carriage A.

Operation

Logs entering the machine through the supply ramp I are picked up by the carriers 58 and deposited into the holders 71 where the logs are gripped between the ram 5 and the log-holders 6 and with continued movement of the carriages A and B the log is carried through the cylindrical cutting head which is shown in detail in Figure 8 whereby the rough outer surfaces of the logs are cut away by the rotary cutters 10 and the surface of the log is sanded by the belt sanders carried by the cutters.

Although it is not desired to be limited to a particular speed, as an example, these cutters travel at a speed of ten thousand R. P. M. with the tubular cutter head on which the cutters are mounted traveling or rotating two thousand five hundred R. P. M.

As the log continues to travel through the tubular cutter head it is engaged by the sanders 35 and after passing through the cutter head the finished logs are deposited upon the platform M.

Having thus fully described my invention what I claim as new and desire to secure by Letters Patent is:

1. In a log shaping machine, the combination which comprises an elongated horizontally disposed frame, a log receiving cylinder positioned on said frame, log holding carriages on the frame, positioned at opposite ends of the cylinder and mounted to travel longitudinally of the frame for carrying logs through said cylinder, a ram

mounted to travel longitudinally in one of said carriages, means for actuating the ram for driving a log longitudinally through the cylinder, means journaling the log receiving cylinder on the frame, means rotating the cylinder, a ring mounted on one end of the cylinder, a plurality of spaced longitudinally disposed shafts journaled in said ring, pinions on said shaft, an internal gear mounted on said frame and positioned to mesh with the pinions on the shafts a plurality of rotary cutters mounted on extended ends of the shafts positioned to extend beyond the end of the cylinder and into the path of a log passing through the cylinder, and means for removing the finished logs from the carriages.

2. In a log shaping machine, the combination which comprises an elongated machine frame, a power carriage mounted in said frame and adapted to travel longitudinally therein, a holder carriage also mounted in the frame and also adapted to travel longitudinally therein, a ram slidably mounted in said power carriage, a power cylinder mounted in said power carriage for actuating said ram toward the holding carriage, a clamping head on said holder carriage and aligned with said ram, a cylindrical cutter head journaled on said frame and positioned between the power and holder carriages, a plurality of radially disposed rotary cutters journaled on said cutter head, gears on said rotary cutters, a stationary gear mounted on said frame and positioned in meshing relation with the gears of the rotary cutters, and means for rotating the cylindrical cutter head whereby the rotary cutters operate on a log carried by the ram and clamping head as the log is carried longitudinally through the cylindrical cutter head by the ram.

3. In a log shaping machine, the combination which comprises an elongated machine frame, a power carriage mounted in said frame and adapted to travel longitudinally therein, a holder carriage also mounted in the frame and also adapted to travel longitudinally therein, a ram slidably mounted in said power carriage, a power cylinder mounted in said power carriage for actuating said ram toward the holding carriage, a clamping head on said holder carriage and aligned with said ram, a cylindrical cutter head journaled on said frame and positioned between the power and holder carriages, a plurality of radially disposed rotary cutters journaled on said cutter head, gears on said rotary cutters, a stationary gear mounted on said frame and positioned in meshing relation with the gears of the rotary cutters, and means for rotating the cylindrical cutter head whereby the rotary cutters operate on a log carried by the ram and clamping head as the log is carried longitudinally through the cylindrical cutter head by the ram.

4. In a log shaping machine, the combination which comprises an elongated machine frame, a power carriage mounted in said frame and adapted to travel longitudinally therein, a holder carriage also mounted in the frame and also adapted to travel longitudinally therein, a ram slidably mounted in said power carriage, a power cylinder mounted in said power carriage for actuating said ram toward the holding carriage, a clamping head on said holder carriages, a plurality of radially disposed rotary cutters journaled on said cutter head, gears on said rotary cutters, a stationary gear mounted on said frame and positioned in meshing relation with the gears of the rotary cutters, and means for rotating the cylindrical cutter head whereby the rotary cut-

ters operate on a log carried by the ram and clamping head as the log is carried longitudinally through the cylindrical cutter head by the ram.

5. A log shaping machine comprising a horizontally disposed rectangular shaped frame having pairs of upper and lower longitudinally disposed parallel bars therein, spaced carriages mounted to travel on said lower bars, a cylindrical cutter head having an opening for logs to pass longitudinally therethrough journaled in the frame and positioned between said carriages, rotating cutters journaled in said cutter head, a ram carried by one of said carriages and mounted to travel longitudinally therethrough, the other of said carriages having a clamping head thereon, means for actuating said ram to clamp a log between the carriages with the log extended through said cutter head and clamped between the ram of one carriage and clamping head of the other carriage, means for actuating said carriages to carry a log through the cutter head and means for rotating the cutter head and cutters carried thereby.

EDWARD WILSON.
